US00D681683S

(12) **United States Design Patent**
Schmelzer et al.

(10) **Patent No.:** **US D681,683 S**
(b4) **Date of Patent:** **** May 7, 2013**

(54) **FUEL DISPENSER**

(75) Inventors: **Anthony E. Schmelzer**, Austin, TX (US); **Daniel C. Harrell**, Georgetown, TX (US); **Daniel Deruntz**, Somerville, MA (US); **Kent W. Robinson**, Quakertown, PA (US); **Eva-Lie Edvardsson**, Solvesborg (SE); **Gian Pangaro**, St. Somerville, MA (US); **Jason Robinson**, Tewksbury, MA (US); **Kevin Burnett**, Round Rock, TX (US); **Russell Haecker**, Round Rock, TX (US); **Timothy Raymond Proulx**, Nashua, NH (US)

(73) Assignee: **Dresser Wayne AB**, Malmo (SE)

(**) Term: **14 Years**

(21) Appl. No.: **29/388,866**

(22) Filed: **Apr. 4, 2011**

(30) **Foreign Application Priority Data**

Oct. 4, 2010 (EM) 001238117-0018

(51) **LOC (9) Cl.** **15-02**

(52) **U.S. Cl.**

USPC **D15/9.2**

(58) **Field of Classification Search** D15/7-9; D23/231, 232, 225; 417/60, 235, 265, 321, 417/355, 358, 363, 359, 410.1, 415-416, 417/405, 900, 43, 554; 60/408, 412; 184/26-37; 415/140-147; 123/495, 509; 166/105.1, 166/105.2, 311

(57) **CLAIM**

The ornamental design for a fuel dispenser, substantially as shown and described.

DESCRIPTION

FIG. 1 is a front, right side perspective view of a fuel dispenser showing our design;

FIG. 2 is a front view thereof;

FIG. 3 is a rear view thereof;

FIG. 4 is a right side view thereof; and,

FIG. 5 is a left side view thereof.

The top and bottom are unornamented and form no part of the claimed design.

1 Claim, 5 Drawing Sheets
